UNITED STATES PATENT OFFICE.

ELIJAH H. DAVIS, OF MIDLAND, MARYLAND.

CLOSURE DEVICE.

1,168,608.

Specification of Letters Patent. Patented Jan. 18, 1916.

Application filed March 22, 1915. Serial No. 16,162.

To all whom it may concern:

Be it known that I, ELIJAH H. DAVIS, a citizen of the United States, residing at Midland, in the county of Allegany and 5 State of Maryland, have invented certain new and useful Improvements in Closure Devices, of which the following is a specification, reference being had to the accompanying drawings.

10 This invention relates to closure devices and has relation more particularly to a device of this general character especially designed and adapted for use in connection with containers; and it is an object of the 15 invention to provide a device of this general character having novel and improved means whereby the discharge opening of a container may be effectively sealed with convenience and facility.

20 Furthermore, it is an object of the invention to provide a novel and improved device of this general character normally carried by the container with which it is adapted to coact and of such a nature as to be highly 25 sanitary.

25 The invention consists in the details of construction and in the combination and arrangement of the several parts of my improved closure device whereby certain important advantages are attained and the 30 device is rendered simpler, less expensive and otherwise more convenient and advantageous for use, all as will be hereinafter more fully set forth.

35 The novel features of the invention will be carefully defined in the appended claims.

In order that my invention may be the better understood, I will now proceed to describe the same with reference to the 40 accompanying drawings, wherein—

Figure 1 is an elevational view illustrating a closure device constructed in accordance with an embodiment of my invention, the coacting container being disclosed in 45 fragment; Fig. 2 is a vertical sectional view taken through the device as disclosed in Fig. 1, with the clamping member in elevation; and Fig. 3 is a sectional view taken through a cap member constructed in accordance with a further embodiment of my 50 invention.

As disclosed in the accompanying drawings, C denotes a container provided with a discharge neck N and of such configuration in longitudinal section to afford an annular shoulder 1 at a predetermined point

inwardly of the outer end of the neck and with the periphery of the neck intermediate the shoulder and the outer end disposed, as indicated at 2, on a predetermined bevel. 60

Adapted to coact with the neck N of the container is the cap member 3 having the inner surface of the annular flange 4 thereof disposed on a bevel corresponding to the bevel 2 so that when said cap member is 65 in applied position, a perfect seal is assured whereby the possibility of the contents of the container being accidentally discharged with the cap in applied position is eliminated. The outer marginal portion 70 of the flange 4 and its inner wall is provided with an annular groove or channel 5 in which is adapted to be secured a gasket whereby an effective sealing of the container by the cap member 3 is further 75 assured. The gasket 6 may be of rubber, cork or any other material which may be employed with facility. The inner surface of the cap member 3 adjacent the flange 4 is provided with an annular groove or channel 7 concentric to the axial center of the member 3 and in which is positioned the gasket 8 of suitable material, said gasket being arranged for contact with the outer edge of the neck N when the member 3 is 80 applied and serving for a purpose which is believed to be self-evident.

Produced in the outer surface of the member 3 at the axial center thereof is the threaded recess 9 in which is adapted to be 90 engaged the lower extremity of the post or arm 10, said post being provided with an elongated longitudinally disposed slot 11 through which is directed the clamping member 12, herein set forth as substantially 95 U-shape in form, having its free extremities pivotally engaged with the eyes or loops 14 carried by the lever or yoke member 15. The lever or yoke member 15 is pivotally engaged with the anchoring wire 100 or member 16 suitably secured around the neck N inwardly of and immediately adjacent the annular shoulder 1, hereinbefore referred to. As is believed to be self-evident, requisite rocking movement imparted 105 to the lever or yoke member 15 will result in the clamping member 12 effecting the desired engagement of the member 3 upon the neck N.

Loosely mounted upon the post 10 are the 110 reversely disposed caps 17 positioned intermediate the clamping member 12 and the

member 3 and arranged between the caps 17 is an expansible member 18, herein disclosed as a conventional coil spring, embracing the post 10. The expansible member 18 serves to facilitate the application of the member 3 in operative position and also assists in its removal, as is believed to be self-evident to those skilled in the art to which my invention appertains. I also find it of advantage to have the portion of the clamping member 12 disposed through the slot 11 of the post 10 provided with the downwardly disposed substantially V-shape extension 19 extending within the perforation 20 of the upper cap 17 through which the post 10 is directed whereby the requisite relative movement of the caps 17 is facilitated under the influence of the lever or yoke member 15.

20 The member 3 may be formed of any material which may be employed with success, but in certain instances I find it of advantage to employ a member as illustrated in Fig. 3 of the accompanying drawings, and 25 wherein said member is disclosed as comprising a shell 21 of metal and of desired configuration and provided with a filling 22 of celluloid or other sanitary substances, said shell being perforated, as indicated at 30 23, whereby the filling and the shell may be firmly united.

From the foregoing description, it is thought to be obvious that a closure device constructed in accordance with my invention is of an extremely simple and comparatively inexpensive nature and is particularly well adapted for use by reason of the convenience and facility with which it may be assembled, and it will also be obvious that 35 my invention is susceptible of some change and modification without material departure from the principles and spirit thereof and for this reason I do not wish to be understood as limiting myself to the precise

arrangement and formation of the several 45 parts herein shown in carrying out my invention in practice.

I claim:

1. In combination with a container provided with a discharge neck, a closure member therefor, a post projecting from the closure member at substantially its axial center and provided with an elongated slot, a clamping member disposed through the slot of the post, operating means carried by the container coacting with the clamping member, reversely disposed caps loosely mounted upon the post and interposed between the clamping member and the closure member, the outer cap being provided with a perforation, the portion of the clamping member disposed through the slot of the post being provided with an extension directed within the opening of the cap, and an expansible member interposed between the 65 caps.

2. In combination with a container provided with a discharge neck, a closure member therefor, a post projecting from the closure member at substantially its axial center 70 and provided with an elongated slot, a clamping member disposed through the slot of the post, operating means carried by the container coacting with the clamping member, reversely disposed caps loosely mounted upon the post and interposed between the clamping member and the closure member, and an expansible member interposed 75 between the caps, the portion of the clamping member disposed through the slot of the post being provided with an extension interlocking with the adjacent cap.

In testimony whereof I hereunto affix my signature in the presence of two witnesses.

ELIJAH H. DAVIS.
